UNITED STATES PATENT OFFICE.

SUMNER A. BÉMIS, OF SPRINGFIELD, MASSACHUSETTS, ASSIGNOR TO BEMIS CAR TRUCK COMPANY, OF NEW YORK, N. Y., A CORPORATION OF NEW JERSEY.

RAILWAY-CAR TRUCK-FRAME.

SPECIFICATION forming part of Letters Patent No. 761,648, dated June 7, 1904.

Application filed October 5, 1903. Serial No. 175,885. (No model.)

To all whom it may concern:

Be it known that I, SUMNER A. BÉMIS, a citizen of the United States of America, and a resident of Springfield, in the county of Hampden and State of Massachusetts, have invented certain new and useful Improvements in Railway-Car Truck-Frames, of which the following is a full, clear, and exact description.

This invention relates to improvements in trucks for railway-cars, and pertains more particularly to what is termed the "truck-frame," or that department of the truck which serves to carry what may be regarded as the "truck equipments"—such, for instance, as the 15 brake mechanism and the motor—such truck-frame being independent of the department or portion of the truck which constitutes the primary support for the car-carrying bolster or bolsters, although the truck-frame is adapted for such a combination with the car-supporting bolster as to constrain and 20 guide the same in the up-and-down movements thereof and in such slight degree of transverse play as the bolster may desirably be designed 25 to have.

The improved truck-frame is constructed more particularly with reference to making what is termed a "built-up" truck in the larger constructions, so that such frame may 30 have an unusual degree of strength and rigidity and may be produced in a practical and convenient manner, which would not be the case were such frame made as a single cast structure.

The invention consists in parts formed and combined or arranged and connected, all substantially as hereinafter fully described, and set forth in the claims.

The improved truck-frame is shown in the 40 accompanying drawings, in which—

Figure 1 is a side elevation, the right-hand portion thereof showing a half of one side section of the truck-frame, while the left-hand portion of the view shows not only the remainder 45 of the side section of the truck-frame, but it shows the journal-box and car-wheel, the portion of the truck structure which supports the

transom-bolster for carrying the car and such transom-bolster, and the spring-sustained car-supporting bolster. Fig. 2 is a plan view of a 50 one end half of one side section of the truck-frame, on a somewhat larger scale than Fig. 1. Fig. 3 is a vertical cross-sectional view as seen in the direction of the arrow beyond the plane indicated by line 3 3, Fig. 1, the car-supporting bolster and equalizing-bar not shown. Fig. 4 is a vertical cross-sectional view as seen in the direction of the arrow beyond the plane indicated by the line 4 4, Fig. 1, which intersects the equalizing-bar, which is here included. Fig. 5 is a side elevation in detail 55 of a member of the truck-frame which constitutes the centrally-located jaws between which the car-supporting bolster is engaged. Fig. 6 is a side elevation in detail of one set 60 of the pedestals combined in the truck-frame at a location properly relative to one of the journal-boxes.

Similar characters of reference indicate corresponding parts in all of the views. 70

In this truck-frame, A A² represent the inner and outer pedestals, the same being separately formed and arranged in separation, as shown, to give space for occupancy and guidance between and against them of the journal-boxes B of the truck, one of which journal-boxes is shown at the left of Fig. 1, said pedestals having the inner straight vertical-facing surfaces. Each of the inner pedestals A is formed with parallel extension-webs a a, 75 understood as fitted between the end portions of the outer and inner side bars C C² and securely fastened thereto by the bolts d, said inner and outer side bars being arranged in parallelism and separation and advantageously 80 composed of rolled refined iron-bar stock, while the pedestals are practically produced from cast-steel with a reinforcing cross-web f³ between the extensions a a.

D represents the part which comprises the 90 inner and outer pair of jaws f f, the same being arranged in separation, as shown in the side elevation, and having the lower longitudinally-ranging bar-like inner and outer unit-

ing members $f^2 f^2$, which uniting members may be transversely united by a similar connecting-web f^3 , the whole double-sided structure $f^2 f^2$ being in practice formed of malleable iron, and the thickness and distance of separation of the longitudinally-ranging bar-like members $f^2 f^2$ are such as to enable such last-named members to be closely disposed within and along and against the inner sides 5 of the side bars C and C³, these closely-fitting parts being rigidly confined by the bolts y y. The jaws may be separately formed in opposite side sets and bolted, respectively, to the outer and inner side bars C C³. The outer ends of 10 the bar-like and uniting base portions of the jaw-comprised structure may be located more or less near to the ends of the wings or webs of the inner pedestals, which are fitted and connected, as before mentioned, within the said 15 paired and separated side bars.

F represent blocks for resisting the thrust of the car-supporting bolster, (indicated at O in Fig. 1,) these members F being fitted between each pair of the upstanding jaws f and 20 securely fastened thereto by the bolts e. The edges of the said bolster thrust-blocks which are toward the jaw-opening are located somewhat inside of the inner edges of the jaws, so that, in effect, a comparatively wide vertical 25 groove i is produced at the opposite inner edges of both said jaws, in which when the truck is assembled the bolster chafing-blocks H may fit and be guided vertically in unison 30 with the movements of the bolster and constrained against undesirable play in a transverse line of the truck.

Each bolster thrust-block has a longitudinal extension web or bracket g of rabbeted or 35 step form and level with similar bracket-webs h and h³ on the inner and outer pedestals, receiving connection therewith by bolting the top bars G thereto, each one of these top bars extending longitudinally across from a bolster thrust-block f to and along over the tops 40 of the pedestals in bearing and bolted at j to the bracket-webs thereof and are further extended obliquely downwardly, as at k, thence extended longitudinally horizontally, as at k², and then vertically, as at k³.

50 Each of the outer pedestals has an outer longitudinally-extending bracket-lug o, connected to which is a tie-bar p, the same extending to and having connection with the downturned end k³ of the top bar at the extreme 55 end of the truck.

J represents the end tie-bar, the same being bolted to the downturned portion k³ of the top bar and the angularly-turned end of the tie-bar p, setting against and being clamped 60 to the inner face of the said end tie-bar.

Each of the top bars G makes a top chord for each trussed half of the truck-frame, and the trussed structure is furthermore reinforced by the intermediate braces q, extending 65 between the bracket-lugs of the outer

pedestals and the extremities l of the top bars G at a different angle from that of the tie-bars p.

The bottoms of the inner and outer pedestals are united in the usual manner by the pedestal tie-bars s, as shown, and the spring-caps L above the journal-boxes are held up to the upper tie-bars G each by the bolt t, and a reinforcing plate or bar u overlies the pedestals, resting on and being bolted to the top bars G.

The truck-frame, of which at each side of the truck are counterparts of the structure shown and described united by the end tie-bars J and also by centrally-located tie-bars, 70 may be constructed for large and heavy trucks in a durable, strong, and reliable manner and with comparative convenience, and the structure as described and shown enables the combination therewith of the equalizing-bar M, 75 having the angular end portions thereof resting on the tops of the journal-boxes, said equalizing-bar, through the half-elliptic spring W, sustaining the bolster O, on which the car is carried, for up-and-down yielding 80 movements, it being perceived that portions of the equalizing-bar may be disposed between the longitudinally-ranging side portions of 85 truck-frame described.

Having thus described my invention, what I claim, and desire to secure by Letters Patent, is—

1. In a truck-frame, in combination, an intermediately-located part comprising opposite pairs of upstanding jaws f f, with a bolster-accommodating space therebetween, and having longitudinally-ranging base portions f², inner and outer side bars bolted to the base members f² and extended endwise therebeyond, journal-box pedestals having extensions arranged alongside of said inner and outer side bars and bolted thereto, and uniting connections between upper portions of the jaws and upper portions of the pedestals.

2. In a truck-frame, in combination, an intermediately-located part comprising opposite pairs of upstanding jaws f f, with a bolster-accommodating space therebetween, and having longitudinally-ranging base portions f², inner and outer side bars bolted to the base members f², and extended endwise therebeyond, journal-box pedestals having extensions arranged alongside of said inner and outer side bars and bolted thereto, bolster thrust-blocks, fitted between and bolted to the jaws f f, and top bars G, overlying on, and bolted to, and extended between, the upper portions of the bolster thrust-blocks and the pedestals.

3. In a truck-frame, in combination, inner and outer pairs of jaws, each comprising the upstanding jaw members f f, and the uniting base member f², inner and outer side bars arranged in parallelism and bolted to the base members f², and extended endwise therebeyond, journal-box pedestals, the inner ones of

each pair having parallel extensions arranged alongside of said outer and inner side bars, and bolted thereto, a thrust-block fitted between the transversely opposite pairs of jaws 5 and bolted thereto, and top bars G connected to the thrust-blocks and extending therefrom to and over the tops of the inner and outer pedestals and connected rigidly therewith.

4. In a truck-frame, in combination, an intermediately-located part comprising opposite pairs of upstanding jaws f f, with an upwardly-opening bolster-space therebetween, and having longitudinally-ranging base portions f² uniting each side pair of said jaws, inner and outer longitudinally-ranging side bars C C², arranged sidewise against said base portions f², and having bolts connecting such parts, and said side bars extending longitudinally beyond the ends of the base portions of the jaw-comprising parts, the separated outer and inner pedestals, the inner ones having longitudinally inwardly extending members arranged facewise against the extremities of the side bars and bolted thereto, blocks fitted between and connected to upper portions of said pairs of jaws f f, and the top bars G G overlying, bolted to, and extended between, the tops of said blocks and the pairs of pedestals.

5. In a truck-frame, in combination, an intermediately-located part comprising opposite pairs of upstanding jaws f f, with an upwardly-opening bolster-space therebetween, and having longitudinally-ranging base portions f² uniting each side pair of said jaws, inner and outer longitudinally-ranging side bars C C², arranged sidewise against said base portions f², and having bolts connecting such parts, and said side bars extending longitudinally beyond the ends of the base portions of the jaw-comprising parts, the separated outer and inner pedestals, the inner ones having longitudinally inwardly extending members arranged facewise against the extremities of the side bars and bolted thereto, blocks fitted between and connected to upper portions of said pairs of jaws f f, and the top bars G G overlying, bolted to, and extended between, the tops of said blocks and the pairs of pedestals and further endwise extended terminating at a level lower than the tops of the pedestals, and tie-bars connecting the outer pedestals and the extremities of the top bars.

6. In a truck-frame, in combination, an intermediately-located part comprising opposite pairs of upstanding jaws f f, with an upwardly-opening bolster-space therebetween and having longitudinally-ranging base portions f² uniting each side pair of said jaws, inner and outer longitudinally-ranging side bars C C², arranged sidewise against said base portions f², and having bolts connecting such parts, and said side bars extending longitudinally beyond the ends of the base portions of the jaw-comprising parts, the separated inner and outer pedestals having the horizon-

tal bracket extensions h h² at their tops, and the inner pedestals having longitudinally inwardly extending members arranged facewise against the extremities of the side bars, and bolted thereto, the bolster thrust-blocks F F fitted between and connected to upper portions of said pairs of jaws f f, and having the horizontal bracket extensions g g, and the top bars G G overlying the bracket extensions of said thrust-blocks and of said inner and outer pedestals, and bolted thereto, and spanning the spaces at either side of the jaw-opening, between the thrust-blocks, and the inner pedestals, and between the pairs of pedestals.

7. In a truck-frame, in combination, an intermediately-located part comprising opposite pairs of upstanding jaws f f with an upwardly-opening bolster-space therebetween and having longitudinally-ranging base portions f² uniting side pairs of said jaws, inner and outer longitudinally-ranging side bars C C² arranged sidewise against and along said base portions f², and bolted thereto, and said side bars extending longitudinally beyond the ends of the base portions f², the separated inner and outer pedestals A and A² having the horizontal top bracket extension h and h², each inner pedestal having a downwardly and longitudinally inwardly extending portion a, arranged facewise against and bolted to an extremity of the respectively-adjacent side bar, and each outer pedestal having at its lower portion a longitudinally outwardly extending bracket o, the bolster thrust-block F fitted between and bolted to upper portions of the pairs of jaws f f, being arranged with their inner edges removed from the inner edges of the jaws, whereby the grooves i for bolster chafing-blocks are produced, and said thrust-blocks having at their tops the bracket extensions g g, and the top bar G extending horizontally and longitudinally from a position over and against each bracket extension g, over and upon the pedestal-brackets h and h² and continued downwardly and further endwise and terminating in the angular portion k³, bolts connecting said top bars with the several said brackets, and the tie-bars p connecting the lower outer pedestal-brackets o with the said top bar angular members k³, substantially as described.

8. In a truck-frame, in combination, an intermediately-located part comprising opposite pairs of upstanding jaws f f with an upwardly-opening bolster-space therebetween and having longitudinally-ranging base portions f² uniting side pairs of said jaws, inner and outer longitudinally-ranging side bars C C² arranged sidewise against and along said base portions f², and bolted thereto, said side bars extending longitudinally beyond the ends of the base portions f², the separated inner and outer pedestals A and A² having the horizontal top bracket extension h and h², each inner pedestal having a downwardly and longitudi-

nally inwardly extending portion a , arranged facewise against and bolted to an extremity of the respectively adjacent side bar, and each outer pedestal having at its lower portion a longitudinally outwardly extending bracket o , the bolster thrust-block F fitted between and bolted to upper portions of the pairs of jaws f, f' , and having at their tops the bracket extensions g, g' , and each top bar extending 5 horizontally and longitudinally from a position over and against each bracket extension g over and upon the pedestal-brackets h and h^2 and having the downwardly-continued inclined portion k , the longitudinally-continued portion k^2 and the downwardly-terminating portion k^3 , bolts connecting said top bars with the several said brackets, the tie-bars p connecting the lower outer pedestal-brackets o with the said top-bar angular members k^3 , and 10 the braces q , connected and extended between the pedestal-brackets o and the portions k^2 of the top bars.

9. In a truck-frame, in combination, an intermediately-located part comprising opposite 25 pairs of upstanding jaws f, f' with an upwardly-opening bolster-space therebetween and having longitudinally-ranging base portions f^2 uniting side pairs of said jaws, inner and outer longitudinally-ranging side bars C, C^2 arranged 30 ranged sidewise against and along said base portions f^2 , and bolted thereto and said side bars extending longitudinally beyond the ends of the base portions f^2 , the separated inner and outer pedestals A and A^2 having the horizontal top bracket extension h and h^2 , each

inner pedestal having a downwardly and longitudinally inwardly extending portion a , arranged facewise against and bolted to an extremity of the respectively adjacent side bar, and each outer pedestal having at its lower portion a longitudinally outwardly extending bracket o , the bolster thrust-block F fitted between and bolted to upper portions of the pairs of jaws f, f' , and having at their tops the bracket extensions g, g' , and the top bar extending horizontally and longitudinally from a position over and against each bracket extension g over and upon the pedestal-brackets h and h^2 and continued downwardly and further endwise and terminating in the angular portion k^3 , bolts connecting said top bars with the several said brackets, the bars u, u on the top bars over the pairs of pedestals, the spring-caps next under the top bars in the spaces between the pedestals, bolts extending 45 through the said caps, top bars and superimposed bars u , and the tie-bars p connecting the lower outer pedestal-brackets o with the said top-bar angular members k^3 , and the tie-bars J secured to the top-bar members k^3 and 50 extending crosswise of the truck-frame, substantially as described.

Signed by me at Springfield, Massachusetts, in presence of two subscribing witnesses, this 25th day of September, 1903.
